United States Patent Office

Des. 198,621
Patented July 14, 1964

198,621

GARBAGE CAN CADDY

Joseph J. Juen, Melrose, Minn., assignor to Inter-Marc Corporation, Alexandria, Minn., a corporation of Minnesota

Filed Oct. 1, 1963, Ser. No. 76,818

Term of patent 14 years

(Cl. D14—3)

FIG. 1

FIG. 4

FIG. 2

FIG. 3

FIG. 1 is a front perspective taken from one end of a garbage can caddy embodying my new design;

FIG. 2 is a top plan view;

FIG. 3 is a side elevational view; and

FIG. 4 is an end elevational view.

The dominant features of my design reside in the portions shown in full lines.

I claim:

The ornamental design for a garbage can caddy, substantially as shown and described.
